(57) **CLAIM**

The ornamental design for an adaptor as shown and described.

DESCRIPTION

FIG. 1 is a first perspective view of our new design.

FIG. 2 is a second perspective view of our new design.

FIG. 3 is a back view thereof.

FIG. 4 is a front view thereof.

FIG. 5 is a right-side view thereof.

FIG. 6 is a left-side view thereof.

FIG. 7 is a top view thereof.

FIG. 8 is a bottom view thereof.

FIG. 9 is a perspective view of another embodiment of our new design.

FIG. 10 is a front view thereof.

FIG. 11 is a back view thereof.

FIG. 12 is a left-side view thereof.

FIG. 13 is a right-side view thereof.

FIG. 14 is a top view thereof.

FIG. 15 is a bottom view thereof.

FIG. 16 is a perspective view of a further embodiment of our new design.

FIG. 17 is a front view thereof.

FIG. 18 is a back view thereof.

FIG. 19 is a left-side view thereof.

FIG. 20 is a right-side view thereof.

FIG. 21 is a top view thereof; and,

FIG. 22 is a bottom view thereof.

The broken lines in the figures illustrate portions of the adaptor that form no part of the claimed design.

1 Claim, 22 Drawing Sheets
